UNITED STATES PATENT OFFICE.

CHARLES SCHLOSSOW, OF DETROIT, MICHIGAN, ASSIGNOR TO STANDARD SANITARY MANUFACTURING COMPANY, OF PITTSBURG, PENNSYLVANIA, A CORPORATION OF NEW JERSEY.

DESIGN FOR A FLUSHING-TANK.

SPECIFICATION forming part of Design No. 35,898, dated May 6, 1902.

Application filed April 14, 1902. Serial No. 102,937. Term of patent 7 years.

To all whom it may concern:

Be it known that I, CHARLES SCHLOSSOW, a citizen of the United States, residing at Detroit, in the county of Wayne and State of Michigan, have invented and produced a certain new and original Design for a Flushing-Tank, of which the following is a specification, reference being had therein to the accompanying drawing, which is a perspective view.

A is a body of general oblong rectangular form and having rounded corners between the front and ends.

B is a plain panel forming a portion of the front of said body.

C represents vertical columns arranged upon said front on opposite sides of said plain panel and adjacent to said rounded corners. These columns are rounded in cross-section and are longitudinally shaped and fluted.

D and E are respectively the top and bottom, which project beyond the front and have correspondingly-shaped edges.

F and G are rounded moldings of waving contour, respectively, between said top and bottom and said plain panel.

The leading feature of the design is the body of general oblong rectangular form, having rounded corners between front and side, the plain front panel, the vertical columns at opposite sides of said panel adjacent to said rounded corners and being longitudinally shaped, the top and bottom projecting beyond the front and having shaped edges, and the rounded molding of waving contour forming a top and bottom border for said panel.

What I claim as my invention is—

The design for a flushing-tank, substantially as herein shown and described.

In testimony whereof I affix my signature in presence of two witnesses.

CHARLES SCHLOSSOW.
